HANDLE FOR A QUICK RELEASE PIN

Walter H. Dickman, P.O. Box 398,
Huntington Station, N.Y.

Filed Oct. 1, 1963, Ser. No. 76,815

Term of patent 14 years

(Cl. D54—9)

FIG. 1

FIG. 2

FIG. 3

FIG. 5

FIG. 1 is a perspective view of a handle for a quick release pin embodying my new design,

FIG. 2 is a top view,

FIG. 3 is a side view, the other side being essentially the same,

FIG. 4 is an end view, the opposite end being essentially the same, and

FIG. 5 is a bottom view.

The broken line showing is for illustrative purposes only.

I claim:

The ornamental design for a handle for a quick release pin, substantially as shown and described.
